UNITED STATES PATENT OFFICE

2,536,425

HEATER

Charles F. Daly, Boston, Mass.

Application April 5, 1948, Serial No. 18,980

2 Claims. (Cl. 122—145)

1

My present invention is a novel and improved tubular heater utilizing an immersed multi-pass water tube calandria and includes a novel combination of the tubes as a part of the baffle arrangement.

My present construction results in an exceptionally high degree of efficiency in extracting heat from the combustion gases as they are conducted around the tubes and baffles from the heat generating chamber to the flue. Thus by utilizing a plurality of calandria or a plurality of baffles and separating the tubes into distinct portions of the path of the combustion gases from the heater to the flue, I am enabled to bring the water temperature in the boiler to a high efficiency of heat before the combustion gases escape thru the flue.

Furthermore, my present arrangement is extremely simple in construction, readily facilitates cleaning when desired, and will maintain its efficiency with any type of fuel.

Further features, advantages, and novel combinations will be hereinafter more fully pointed out and claimed.

Referring to the drawings illustrating preferred embodiments:

Fig. 1 is a diagrammatic cross-sectional view of a standard type of heater embodying one form of my invention;

Fig. 2 is a cross-sectional view on the line 2—2 of Fig. 1;

Fig. 3 is a corresponding view of a modification in which the immersed water tubes are in a plurality of sections, and

Fig. 4 is a cross-sectional view on the line 4—4 of Fig. 3.

As shown in Fig. 1, a heater of any suitable size, type, and area for the purpose to which it is to be applied is illustrated, having a water jacket and a plurality of immersed tubes forming the calandria which are divided by one or more baffles into a series of passages for the products of combustion from the heating chamber to the flue. As shown, the heater comprises an outer jacket casing 1, bottom 2, and removable top 3, constituting the outer wall of the heater. A fire box has an inner wall 5, bottom 6, and top 7, preferably domed as illustrated in Fig. 1, and with a feed door 10 with side walls 11 and top and bottom flanges 12 and 13 opening thru to the fire box 15 and, thus, enclosing the water chamber 20 in combination with the outer casing 1. A water supply pipe 22 to any suitable source is provided at the bottom and an outlet 21 at the top, as shown, for steam or hot water flowing from the heater.

The heater is sufficiently high in extent to contain the water chamber 24 between the casing 1 and an inner partition 25 formed with top and bottom frames 26 and 27, which contain a plurality of tubes 30—30 extending from the lower water chamber 20 to the upper water chamber 24. These water tubes 30 are open at each end and held with a wedging fit or welded, if desired, in appropriate openings in the top and bottom frames 26 and 27, which tubes are thus in open communication between the water in the top chamber 24 and the lower one 20.

The side walls 25 and 26 may be secured in any suitable manner to the casing 1 and to support the same and the plurality of tubes in position as shown, a convenient means being the clean-out openings thru the side walls as indicated at 33, 34, and 35, together with the walls 36 of the flue opening 40. Intermediate the frame members or tube plates 26 and 27 I supply one or more baffle plates, shown here as one plate 44, having a plurality of openings therein thru which the tubes 30 are fitted, also by a wedging water-tight fit, or they may be welded thereto, as indicated at 45. This baffle plate 44 extends diametrically across the upper part of the heater, leaving an opening from the lower part of the baffle to the upper, as indicated at 48. Thus the products of combustion from the fire box 50 extending upwardly thru a flue opening 50 is deflected by the intermediate baffle plate 44 in the direction shown by the arrows surrounding the water-immersed tubes 30, and then in reverse direction around the upper part of the immersed tube 30 and out of the flue 40.

I may, if desired, arrange a plurality of such intermediate baffle plates, thus giving a series of draft-conducting areas for the products of combustion from the fire box 15 to the draft outlet 40, and thereby I am enabled to maintain the combustion gases in the water tube calandria area of the heater, thereby extracting the heat from the combustion gases with a minimum of loss.

Referring to the modified form shown in Figs. 3 and 4, I have illustrated a substantially similar heater construction with the outer casing 1 and top 3 but with the fire box formed with walls 60, top 61, and bottom 62, thus enclosing the lower and upper water chambers 20 and 24 as already described, and with the top and bottom flanges 26 and 27 substantially as already described. In this form, however, I provide a series of immersed water tube calandria, water tubes 65—65 extending between tight fitting recesses in the top plate 60 and a lower supporting plate 68, and

thereby opening into a central water chamber recess or manifold 70. A second set of water tube calandria 71-71 are fitted between the plate 75 and the lower plate 27, as shown in Fig. 3. The intermediate baffles 66 and 75 are united around the area by a vertical partition 77 to thus insure the tightness of the water jacket and manifold and conduct the products of combustion from the fire box 78 thru the opening 80 to the draft outlet 40 in the direction of the arrows, conducting the heat around the immersed sections of the different sets of immersed tubes 65 and 71 as well as heating the water in the jacket 24 and manifold 70.

In this form, I have illustrated a lowermost water-receiving chamber 81 around the base of the fire box into which the heated water will circulate thru a series of openings 82 in the rim 84 of the bottom plate 62 of the fire box.

Thus, it will be seen that by utilizing a plurality of water tube calandria in combination with baffle plates or a plurality of sets of calandria, opening into different portions of the jacketed water chamber in a heater and conducting the flue gases therearound, I have produced a novel, simple, and efficient construction with a high degree of heat transfer efficiency.

I claim:

1. A boiler of the Scotch marine type comprising a combustion chamber, a shell spaced from said combustion chamber and completely surrounding the same, an opening at the bottom of said shell to admit water to the space between said shell and the walls of said combustion chamber, and risers leading from the top of said shell to the upper part of said boiler, flues communicating with said combustion chamber traversing said boiler and being traversed by said risers, and being adapted and arranged to conduct hot gases of combustion back and forth through said boiler, 40

thereby providing hot surfaces in contact with the main boiler water supply and further heating the water in said risers passing through said flues, said risers being so positioned in the path of said flue gases as to delay the flow thereof and to cause them to yield maximum heat before escaping to the stack.

2. A boiler of the kind described, comprising a combustion chamber, an outer shell spaced from said combustion chamber and partially surrounding the same, an opening at the bottom portion of the shell to admit water to the space between said shell and the walls of said combustion chamber, a plurality of water tubes extending vertically from adjacent the top of the combustion chamber to the upper portions of said boiler, a flue extending from said combustion chamber traversing said boiler and being traversed by said water tubes, baffle plates cooperating with the water tubes to conduct gases of combustion back and forth thru the boiler providing hot surfaces in contact with the main boiler water and further heating the water in said tubes, said tubes being so positioned in the path of the flue gases as to delay the flow thereof and cause them to yield maximum heat before escaping out of the flue.

CHARLES F. DALY.
